TRANSMITTING APPARATUS FOR
COMMUNICATION SYSTEMS

Leland D. Whitelock, Wilkinsburg, and Ralph K. Crooks, Sharpsburg, Pa., assignors to The Union Switch & Signal Company, Swissvale, Pa., a corporation of Pennsylvania

Application April 22, 1941, Serial No. 389,762

10 Claims. (Cl. 179—1)

Our invention relates to transmitting apparatus for communication systems, and more particularly to such apparatus for telephone systems using suppressed carrier transmission.

Communication systems which provide carrier telephony are in general use and in many instances suppressed carrier single side band transmission is employed. Such communication systems are, for example, provided for railway trains where both telephoning and signaling between a wayside station and a station on a train, or between two stations located one on each of two trains, or between two spaced stations on the same train are required. The telephoning is preferably effected by suppressed carrier single side band transmission while signaling and calling is effected by the transmission of the equivalent of the carrier modulated by a single preselected frequency within the voice frequency band. In such system, most satisfactory operation of the transmitting apparatus and of the system in general, is obtained when the output of the transmitting apparatus is of substantially the same energy level for the signaling and calling currents as for the telephone current, because over-energization of the usual power amplifier and other equipment just ahead of the transmitting circuit as well as a poor wave shape and harmonics may result if a high energy level of the signaling and calling currents is used.

In view of the circumstances recited above, a feature of our invention is the provision of novel and improved transmitting apparatus for communication systems.

Another feature of our invention is the provision in transmitting apparatus for communication systems using suppressed carrier single side band transmission of novel and improved means for providing a signaling or a calling current.

Again, a feature of our invention is the provision of novel control and switching means for transmitting apparatus of the type here involved wherewith either a condition for delivering a suppressed carrier single side band telephone current at a desired energy level or a condition for delivering a signaling or calling current of a single frequency preselected within the side band and at substantially the same energy level as that of the telephone current may be established.

Other objects, advantages and features of our invention will appear as the specification progresses.

The above features, advantages and objects of our invention, we attain by including in the trans-

mitting apparatus of a communication system a balanced modulator and a special control and switching means. The balanced modulator includes two electron tubes, the plate circuits of which tubes include respective portions of a primary winding of a modulator output transformer disposed in a push-pull arrangement. The grid circuits of the two tubes are of the balanced type to which a carrier generator or oscillator and a microphone circuit are connected in such a manner that the carrier is modulated by the voice frequency produced in the microphone, the carrier is suppressed and the side bands resulting from such modulation appear in the secondary winding of the modulator output transformer. This secondary winding is connected to the associated transmitting circuit preferably through a filter proportioned to pass a particular one of the side bands only. If further amplification of the selected side band is desired, the necessary stages of amplification are interposed between the filter and the transmitting circuit.

The control and switching means includes a special shunt circuit for the modulator and circuit switching devices preferably in the form of relays. One such switching device or relay by its position controls the frequency of the carrier current delivered by the generator of the apparatus, the effective or ineffective condition of at least one of the tubes of the modulator and the open or closed condition of the shunt circuit. At a first position of such device or relay, the carrier generator is conditioned to deliver a carrier current of a preselected frequency suitable for modulation by voice frequencies, both tubes of the modulator are made effective and the shunt circuit is open with the result that the transmitting apparatus is conditioned for supplying a suppressed carrier single side band telephone current, the energy level of such current being predetermined by the proportioning of the several parts. At a second position of such switching device or relay, the generator is adjusted for delivering a carrier current of a frequency preselected within the side band of the transmitted telephone current, one tube of the modulator is rendered ineffective and the shunt circuit is closed with the result that the carrier current of this new frequency is amplified by one tube of the modulator only, a certain portion of the output energy is shunted through the closed shunt circuit and the remaining portion of such current is delivered to the secondary winding of the modulator output transformer and passed by the filter to the transmitting circuit as a signaling or call-

ing current. Proper proportioning of the shunt circuit causes that portion of the signaling current delivered to the filter, and in turn to the transmitting circuit, to be of an energy level of the same order as the energy level of the telephone current. That is, this signaling current supplied by the carrier generator is preselected as to its frequency so as to fall within the band of the transmitted telephone current, and a sufficient portion of the signaling current is shunted away from the output of the modulator by the special shunt circuit so as to leave the energy level of the portion of the signaling current applied to the filter to be of the same order as the energy level of the telephone current.

A second switching device or relay is preferably used to govern the connections of the current sources to the apparatus and to govern the effective or ineffective condition of the microphone circuit. At a first position of such second device or relay, the sources of current are disconnected from the plate circuits of the electron tubes of the apparatus, and the apparatus is retained in a standby condition. Such standby condition is desirable in systems of the type here contemplated because the receiving apparatuses at the different stations of the system are energized and in an active condition ready to receive energy from the transmitting circuit, and hence it is desirable that the transmitting apparatus at each station of the system be retained in an ineffective standby condition. At a second position of this second device or relay, power is applied to the plate circuits of the several electron tubes and the transmitting apparatus is made active and ready for transmission of current. The microphone circuit is also rendered effective at this second position of the second device. Preferably, the conditions of the apparatus as effected by the switching devices are interlocked so that signaling current may not be delivered by the carrier generator while telephone communication is going on.

We shall describe one form of apparatus embodying our invention, and shall then point out the novel features thereof in claims.

The accompanying drawing is a diagrammatic view showing one form of transmitting apparatus embodying our invention, and which apparatus is particularly useful for a communication system for railway trains, but is in no manner limited thereto in its use.

Referring to the drawing, the transmitting apparatus comprises a microphone M, a carrier generator G, a balanced modulator BM, a band pass filter BPF, an amplifier AM, a shunt circuit SC, proper sources of current and switching means, the latter of which will be more fully described hereinafter.

Referring first to the balanced modulator BM, it includes two electron tubes 4 and 5 which, as here shown, are of the indirectly heated cathode type, the filaments of these tubes being heated by any convenient means, such as a battery 6. The control grids 7 and 8 of tubes 4 and 5, respectively, are connected to balanced grid circuits of any convenient type, and in the instant application the grids 7 and 8 are connected to the respective outside terminals of a first resistor 9, the center terminal of which is connected to the cathodes 10 and 11 of the tubes through a second resistor 12 and a biasing unit 13 of the potentiometer type. A ground electrode 14 is connected at the junction of resistor 75

12 and biasing unit 13 as will be readily understood by an inspection of the drawing.

The microphone M is included in a circuit which is coupled to the grid circuits of tubes 4 and 5 through a coupling transformer T2 whose secondary winding 27 is connected across the outside terminals of resistor 9. Such microphone circuit can be traced from the top terminal of microphone M as viewed in the drawing over 10 primary winding 30 of transformer T2, impedance 29, wires 28 and 25, front contact 24 of a relay DR to be later described, resistor 23 and ground electrodes 22 and 31 to the lower terminal of microphone M, a by-pass condenser 36 being 15 preferably connected between the ground electrode 31 and primary winding 30. It follows that at such time as relay DR is picked up, closing front contact 24 and current flows in the plate circuits of tubes 4 and 5, as will be shortly explained, the voltage drop across resistor 23 20 serves to energize the microphone circuit with the result that electromotive forces created by speaking into microphone M cause electromotive forces of corresponding frequencies to be applied across resistor 9 of the grid circuits of tubes 25 4 and 5, but that when relay DR is released to open the plate circuits of the modulator tubes, the microphone circuit is made ineffective.

Modulator tubes 4 and 5 are provided with 30 plate circuits having a push-pull arrangement and which circuits are energized from any convenient source of current, which in the present embodiment of the invention consists of a transformer T1 and rectifiers R1 and R2. A primary winding 15 of transformer T1 is connected to the BX and CX terminals of a suitable source of alternating current, such as a generator not shown, while a secondary winding 16 of transformer T1 supplies through the rectifiers R1 and R2 unidirectional current to the plate circuits. 35 To be explicit, the plate circuit for tube 4 can be traced from the top outside terminal of secondary winding 16 of transformer T1 over rectifier R1 in its low resistance direction to wire 17, or from the lower outside terminal of secondary winding 16 over rectifier R2 in its low resistance direction to wire 17, and thence through impedance 18, resistor 19, center terminal of primary winding 20 of an output transformer OT, top half portion of primary winding 20, plate 21 40 of tube 4, intervening tube space to cathode 10 of the tube, biasing unit 13, ground electrode 14, ground electrode 22, resistor 23, front contact 24 of relay DR and wire 25 to the center terminal of secondary winding 16 of transformer T1. 45 Similarly, the plate circuit for tube 5 is the same as the circuit for tube 4 up to the center terminal of primary winding 20 of output transformer OT, and thence through the lower half portion of primary winding 20, wire 53, back contact 54 50 of relay DR, also to be later described, wire 55, plate 26 of tube 5, intervening tube space to cathode 11 of the tube, biasing unit 13, ground electrode 14, and thence to the center terminal of secondary winding 16 of transformer T1 over 55 the same path as traced for the plate circuit of tube 4.

Carrier generator G is connected to the grid circuits of tubes 4 and 5 by being connected across resistor 12, one output terminal of generator G being connected to one terminal of resistor 12 over wire 31 and the other output terminal of generator G being connected to the other terminal of resistor 12 over wire 32 and ground electrodes 33 and 14. The type of gen-

erator G is immaterial and it is shown conventionally for the sake of simplicity. In the present embodiment of the invention it is contemplated that generator G is of the electron tube oscillator type including an oscillating circuit the physical elements of which determine the frequency of the current delivered by the generator. Looking at generator G, a condenser 34 is interposed in the oscillating circuit of the generator over a back contact 35 of relay DR1. When relay DR1 is released closing back contact 35 and condenser 34 is included in the oscillating circuit of the generator, the generator delivers current of a preselected carrier frequency and when relay DR1 is picked up opening back contact 35 and disconnecting condenser 34 from the oscillating circuit the frequency of the current delivered by the generator is raised by a predetermined amount preselected by the capacity of condenser 34. As an aid in the understanding of our invention, we shall assume that generator G delivers a carrier current of 5700 cycles per second when condenser 34 is included in the oscillating circuit of the generator and that the carrier is raised 1050 cycles to 6750 cycles per second when condenser 34 is disconnected from the oscillating circuit. Since 1050 cycles per second falls within the voice frequency range, it is to be seen that the carrier current is raised in frequency by a preselected voice frequency when condenser 34 is disconnected. It is clear that the same results in adjusting the frequency of the output of the generator can be effected by varying the inductance of the tuned or oscillating circuit instead of varying the capacity of the circuit. Also, it is clear that when the band pass filter BPF is adjusted for lower side band transmission, the frequency of the carrier may be decreased to a predetermined frequency, such as 4650 cycles, which is the equivalent of the lower side band of a carrier of 5700 cycles modulated by a 1050 cycle current. The significant point as far as our invention is concerned is the fact that generator G is conditioned to deliver a carrier of a preselected frequency when relay DR1 is released and is conditioned to deliver a carrier of a frequency varying from such preselected frequency by a preselected voice frequency when relay DR1 is picked up. It is to be understood of course that our invention is not limited to the specific frequencies assumed above, and other frequencies can be used if desired.

Consequently when relay DR is picked up closing front contact 24 to complete the plate circuits for tubes 4 and 5, and relay DR1 is released closing back contacts 35 and 54, a carrier of a frequency of 5700 cycles per second is modulated by the voice frequency produced in the microphone circuit, the carrier is balanced out by the push-pull arrangement of the plate circuits of tubes 4 and 5 and the resultant side band electromotive forces are created in secondary winding 37 of the output transformer OT, the energy level of such electromotive forces being predetermined by the proportion of the parts.

Band pass filter BPF has its input terminals connected to secondary winding 37 of transformer OT over wires 38 and 39 and is proportioned to pass a selected one of the side bands and to suppress the other, and we shall assume that the upper side band is passed by the filter BPF and the lower side band is suppressed. It is to be understood, of course, that the band pass filter may be proportioned to select the lower side band and suppress the upper side band if desired. With filter BPF proportioned to pass the upper side

band, it passes a band of frequencies extending from 6200 to 8200 cycles per second, on the assumption that the voice frequency band extends from 500 to 2500 cycles and the carrier is 5700 cycles.

The output terminals of filter BPF are connected by wires 40 and 41 to the input terminals of an amplifier AM whose output circuit is coupled to a transmitting circuit TC through the medium 10 of a coupling transformer T3. Amplifier AM may be of any one of several well-known types and is shown conventionally for simplicity. Amplifier AM would be preferably of the electron tube type, the plate circuit of which includes the primary 15 winding 42 of the coupling transformer T3 whose secondary winding 43 is connected across wires 44 and 45 of the transmitting circuit TC leading to a remote associated station not shown. Preferably another secondary winding 46 of transformer T3 is connected to an indication lamp 47 which lamp is thus illuminated as an indication to the operator of the transmitting apparatus that current is being supplied to the transmitting circuit.

25 A transformer T4 and rectifiers R3 and R4 serve as a source of energy for the plate circuit of amplifier AM, primary winding 48 of transformer T4 being connected to the BX and CX terminals of the source of alternating current over an obvious circuit including front contact 49 of relay DR. Unidirectional current is supplied to the plate circuit of amplifier AM from secondary winding 50 of transformer T4 by a circuit extending from the outside terminals of 30 the secondary winding 50 through either rectifier R3 or R4, as the case may be, to a wire 51 leading to primary winding 42 of transformer T3, the other terminal of which winding is connected to the amplifier, while the other side of the plate circuit extends from another terminal of the amplifier to the center terminal of secondary winding 50 over wire 52. The turn ratio of transformer T4 is proportioned, of course, so as to supply current of the proper voltage for the plate circuit of the amplifier AM. Hence relay DR when released opening front contact 49, causes amplifier AM to be deenergized and the coupling between filter BPF and the transmitting circuit TC to be ineffective, but when relay DR is picked up to close front contact 49, amplifier AM is energized and the coupling between filter BPF and the transmitting circuit is made effective. Relay DR therefore controls at its front contacts 24 and 49 the energization of the plate circuits of the tubes 4 and 5 of the modulator and of the amplifier AM. Also, as described hereinbefore, the energization of the microphone circuit is effected by the voltage drop across resistor 23 placed in the plate circuits of tubes 4 and 5 with the result that relay DR therefore controls the effective or ineffective condition of the microphone circuit.

It should be pointed out at this point that in the event additional amplification of the side band energy created in the secondary winding 37 of transformer OT is not required, then the amplifier AM may be omitted and the wires 40 and 41 leading from the output terminals of filter BPF would be connected directly to the transmitting circuit over a contact controlled by relay DR.

70 Shunt circuit SC is associated with the modulator BM, and includes a resistor 56, preferably of the adjustable type. When relay DR1 is picked up to close front contact 57, this shunt circuit SC is closed across the primary winding 20

of the output transformer OT as can be traced from the top terminal of primary winding 20 over wire 58, resistor 56, front contact 57 of relay DR1 and wire 53 to the lower terminal of winding 20. The function of the shunt circuit SC will appear when the operation of the apparatus is described.

The control of the transmitting apparatus is effected by relays DR and DR1 which may be in turn governed automatically or manually as desired. In the present embodiment of the invention, relays DR and DR1 are governed by two manually operable switches PB1 and PB2, switch PB1 being preferably of the biased spring return push button type, and switch PB2 being preferably of the non-biased type remaining at either its full line or its dotted line position except as moved manually from one position to the other. The control circuits by which switches PB1 and PB2 control relays DR and DR1 will shortly appear.

In describing the operation of the apparatus, we shall first assume that both switches PB1 and PB2 occupy the positions illustrated by the full lines in the drawing, so that the control circuits for relays DR and DR1 are open and both relays released. Under this condition of the relays, the plate circuits of modulator tubes 4 and 5 are open at front contact 24 of relay DR, and the plate circuit of amplifier AM is open at front contact 49 of relay DR with the result the transmitting apparatus is normally at an inactive standby condition.

In preparation for telephone communication, we shall assume that the operator first sends a calling current. The operator under such circumstances would move the switch PB2 to its dotted line position where a control circuit is formed from terminal B of a suitable source of current, such as a battery not shown, over a winding of relay DR, contact 58 of switch PB2 and to terminal C of the same source of current, and relay DR is energized and picked up closing front contacts 24 and 49 and completing the plate circuits for the modulator BM and amplifier AM. A control circuit for relay DR1 is also formed from terminal B over contact 59 of switch PB2, winding of relay DR1, contact 60 of switch PB1 and to terminal C, and relay DR1 is picked up to open its back contacts 35 and 54 and close its front contact 57. The opening of back contact 35 disconnects condenser 34 from the oscillating circuit of generator G and shifts the carrier frequency from 5700 cycles to 6750 cycles per second. The opening of back contact 54 opens the plate circuit of tube 5 of the modulator and that tube is made inactive. The closing of front contact 57 completes the shunt circuit SC across primary winding 20 of transformer OT. The carrier current from generator G is now applied across grid 1 and cathode 10 of tube 4 only and causes the plate circuit of tube 4 to have an alternating current component of the corresponding carrier frequency, since the normal carrier suppression is prevented due to the inactivity of tube 5. The purpose of resistor 56 is to provide a means of reducing the power output of tube 4 to the desired level. A variation in the value of resistor 56 alters the impedance of the output circuit of tube 4, thus effecting a change in the power delivered by the tube to its load. Thus it is seen that tube 4 under these conditions operates as a simple amplifier delivering energy at the signal frequency to the transformer OT. This energy transferred to secondary winding 37

is of the frequency of 6750 cycles per second and hence falls within the pass band for filter BPF which, as stated hereinbefore, is proportioned to pass the upper side band frequencies extending from 6200 to 8200 cycles. Thus the energy now delivered to secondary winding 37 serves as a calling current and is passed by filter BPF to amplifier AM and then is delivered to the transmitting circuit TC through transformer T3. The 10 energy level of this calling current as delivered to secondary winding 37 of transformer OT and in turn to the transmitting circuit TC can readily be preselected by the proportioning of resistor 56 of the shunt circuit. Furthermore, such calling 15 current is supplied by the apparatus to the transmitting circuit as long as switch PB2 remains at its dotted line position and the switch PB1 occupies its normal position.

For the purpose of calling, the operator would, 20 of course, retain switch PB2 at its dotted line position only for a short interval. It is to be seen, however, that if it is desired to transmit such current for an indefinite period for the purpose of signaling, such transmission is effected by retaining the switch PB2 at its second or 25 dotted line position. Also, it is clear that by operating switch PB2 between its two positions in accordance with short and long intervals corresponding to a prearranged code, code signaling current can be supplied to the transmitting circuit. It is to be noted that lamp 47 is illuminated 30 in response to the transmission of such current and hence will indicate to the operator when current is supplied to the transmitting circuit.

Assuming telephone communication is desired 35 after the sending of the calling current, switch PB2 is placed at its normal position and switch PB1 is depressed. With switch PB1 depressed, relay DR is energized over an obvious control circuit including contact 61 of switch PB1 and power is applied to the plate circuits of the several tubes, the same as previously pointed out. With relay DR1 released, generator G is conditioned to deliver a carrier of 5700 cycles and both 40 tubes 4 and 5 of the modulator are active, so that the voice frequencies produced by speaking into the microphone M modulate the carrier current and the carrier is suppressed by the push-pull arrangement of the plate circuits of tubes 4 and 5 leaving the side bands transferred to secondary 45 winding 37 of transformer OT. Filter BPF passes only the upper side band of such modulated current and the current is amplified at amplifier AM and applied to the transmitting circuit TC for transmission to the remote associated station, 50 lamp 47 being illuminated to indicate to the operator such transmission.

As pointed out hereinbefore, the energy level 55 of the telephone current can be predetermined by proper proportioning of the parts. Also, the energy level of the calling and signaling currents can be made of the same order as that of the telephone current by proper proportioning of the shunt circuit SC. Furthermore, the energy of 60 the telephone current and of the calling and signaling currents as delivered to filter BPF and in turn to amplifier AM just ahead of the transmitting circuit can be made of such level that over-energization of these devices, distorted wave 65 shape and harmonics are avoided.

It should be pointed out that, while it is contemplated that the energy level of the calling and signaling currents is governed by rendering one tube of the modulator inactive and by placing 70 a shunt circuit on the modulator output

transformer, the desired value of the calling and signaling currents may be accomplished by rendering one tube of the modulator inactive only and the shunt circuit may then not be required.

It is to be seen, therefore, that we have provided novel and improved transmitting apparatus including control and switching means wherewith a calling and signaling current can be readily supplied and which calling and signaling current can be made of an energy level predetermined by the proper proportioning of a shunt circuit.

Although we have herein shown and described only one form of transmitting apparatus for communication systems embodying our invention, it is understood that various changes and modifications may be made therein within the scope of the appended claims without departing from the spirit and scope of our invention.

Having thus described our invention, what we claim is:

1. In transmitting apparatus for a communication system the combination comprising, a generator operable to deliver a carrier current, a microphone, a balanced modulator including two electron tubes whose input circuits are coupled to said generator and to said microphone to effect a carrier telephone current in the output circuits of the tubes, control means operable to a first and a second position, means including the first position of said control means to adjust said generator to deliver a carrier current of a preselected frequency suitable for said telephone current, means including the second position of said control means to open the output circuit of a selected one of said tubes and to adjust said generator to deliver a carrier current of a frequency equal to said preselected frequency varied by a preselected voice frequency for creating a signaling current in the output circuit of the other tube, and a transmitting circuit coupled to said output circuits for transmission of either the telephone current or of the signaling current.

2. In transmitting apparatus for a communication system using suppressed carrier transmission the combination comprising, a generator operable to deliver a carrier current, a microphone, a balanced modulator including two electron tubes whose input circuits are coupled to said generator and to said microphone, a control means operable to a first and a second position, means governed by said control means at its first position to adjust said generator to deliver a carrier current of a preselected frequency and to connect the output circuits of said tubes in a push-pull arrangement to provide a suppressed carrier telephone current in response to voice frequencies created in said microphone, means governed by said control means at its second position to open the output circuit of a preselected one of said tubes and to adjust said generator to deliver a carrier current of a frequency equivalent to said preselected frequency shifted by a preselected voice frequency to create a signaling current in the output circuit of the other one of said tubes, and means for coupling the output circuits of said tubes to a transmitting circuit.

3. In transmitting apparatus for a communication system using suppressed carrier transmission the combination comprising, a generator normally adjusted to deliver a carrier current of a preselected frequency, a microphone, a balanced modulator including two electron tubes whose input circuits are coupled to said generator and to said microphone to effect a carrier

telephone current in the output circuits of the tubes, a relay deenergized or energized according to a first or a second position of a manually operable switch, means controlled by said relay when deenergized to connect the output circuits of said tubes in a push-pull arrangement to suppress the carrier of said telephone current, means controlled by said relay when energized to condition the generator to deliver a signaling current of a frequency equivalent to said carrier current modulated by a preselected voice frequency, to open the output circuit of a selected one of the tubes and to connect a shunt path including resistance across the output circuit of the other tube; and a transmitting circuit coupled to the output circuits of said tubes for transmission of said suppressed carrier telephone current and of said signaling current.

4. In transmitting apparatus for a communication system using suppressed carrier transmission the combination comprising, a generator normally adjusted to deliver a carrier current of a preselected frequency, a microphone, a balanced modulator including two electron tubes whose input circuits are coupled to said generator and to said microphone to effect a carrier telephone current in the output circuits of the tubes, control means operable to a first and a second position, means including the first position of said control means to connect the output circuits of said tubes in a push-pull arrangement to suppress the carrier of said telephone current, a transmitting circuit, means including a filter effective to pass only a selected one of the side bands of said telephone current to couple said transmitting circuit to the output circuits of said tubes, and means including the second position of said control means to condition said generator to deliver a signaling current of a frequency preselected within the band passed by said filter and to open the output circuit of a preselected one of said tubes.

5. In transmitting apparatus for a communication system using suppressed carrier transmission the combination comprising, a generator normally adjusted to deliver a carrier current of a preselected frequency, a microphone, a balanced modulator including two electron tubes whose input circuits are coupled to said generator and to said microphone to effect a carrier telephone current in the output circuits of the tubes, control means operable to a first and a second position, means including the first position of said control means to connect the output circuits of said tubes in a push-pull arrangement to suppress the carrier of said telephone current, means including the second position of said control means to render inactive a preselected one of said tubes and to condition said generator to deliver a signaling current of a frequency equal to said preselected frequency varied by a preselected voice frequency, and a transmitting circuit coupled to said output circuits for transmission of either said suppressed carrier telephone current or of said signaling current.

6. In transmitting apparatus for a communication system using suppressed carrier transmission the combination comprising, a balanced modulator including two electron tubes the plate circuits of which include respective portions of an output transformer primary winding disposed in a push-pull arrangement, means effective at times to apply to the control grids of said tubes a carrier current of a preselected frequency and a voice frequency current to create in a secondary

winding of said output transformer the side bands of said carrier modulated by voice frequencies, a transmitting circuit, means including a filter effective to pass a preselected one of said side bands only to couple said secondary winding to said transmitting circuit for transmission of such single side band telephone current, means effective at other times to apply to the control grids of said tubes a signaling current of a single frequency preselected within the side band passed by said filter, and control means operable to open the plate circuit of one of said tubes for transmission of such signaling current.

7. In transmitting apparatus for a communication system using suppressed carrier transmission the combination comprising, a balanced modulator including two electron tubes the plate circuits of which include respective portions of an output transformer primary winding disposed in a push-pull arrangement, means effective at times to apply to the control grids of said tubes a carrier current of a preselected frequency and a voice frequency current to create in a secondary winding of said output transformer the side bands of said carrier modulated by voice frequencies, a transmitting circuit, means including a filter effective to pass a preselected one of said side bands only to couple said secondary winding to said transmitting circuit for transmission of such single side band telephone current, means effective at other times to apply to the control grids of said tubes a signaling current of a single frequency preselected within the side band passed by said filter, and control means operable to render only a preselected one of said tubes effective for transmission for said signaling current.

8. In transmitting apparatus for a communication system using suppressed carrier transmission the combination comprising, a balanced modulator including two electron tubes the plate circuits of which include respective portions of an output transformer primary winding disposed in a push-pull arrangement, means effective at times to apply to the control grids of the said tubes a carrier current of a preselected frequency and a voice frequency current to create in a secondary winding of said output transformer the side bands of said carrier modulated by voice frequencies, a transmitting circuit, means including a filter effective to pass a preselected one of said side bands only to couple said secondary winding to said transmitting circuit for transmission of such single side band telephone current, means effective at other times to apply to the control grids of said tubes a signaling current of a single frequency preselected within the side band passed by said filter, a shunt circuit having a predetermined resistance, and control means operable to open the plate circuit of one of said tubes and to connect said shunt circuit across that portion of said primary winding included in the plate circuit of the other tube for transmission of such signaling current at a predetermined energy level.

9. In transmitting apparatus for a communication system using suppressed carrier transmission the combination comprising, a balanced modulator including two electron tubes the plate circuits of which include respective portions of an output transformer primary winding disposed in a push-pull arrangement and the grid circuit of which includes a first resistor having its outside terminals connected one to each grid and its center terminal connected to the cathode of each tube through a second resistor, a carrier current generator connected across said second resistor, a microphone circuit including a microphone connected across said first resistor for modulating the carrier current by the voice frequencies produced in said microphone and creating corresponding suppressed carrier side band telephone currents in a secondary winding of said output transformer, a transmitting circuit, means including a filter effective to pass a selected one of said side band telephone currents only to couple said secondary winding to said transmitting circuit for transmission of such single side band telephone current, a shunt circuit including a resistor; and a control relay effective when picked up to condition said generator to supply a signaling current of a single frequency preselected within the side band passed by said filter, to open the plate circuit of one of said tubes and to close said shunt circuit across said primary winding for transmission of such signaling current at a predetermined energy level.

10. In transmitting apparatus for a communication system using suppressed carrier transmission the combination comprising, a generator normally adjusted to deliver a carrier current of a preselected frequency, a microphone, a modulator including two electron tubes whose grid circuits are coupled to said generator and to said microphone and the plate circuits of which tubes include respective portions of an output transformer primary winding disposed in a push-pull arrangement, said modulator effective to create in a secondary winding of the output transformer the side bands of said carrier modulated by the voice frequencies produced in said microphone with the carrier suppressed; control means effective at times to adjust said generator to deliver a signaling current of a frequency equal to said preselected frequency modulated by a preselected voice frequency, to open the plate circuit of one of said tubes and to connect a shunt resistance across the outside terminals of said output transformer primary winding for creating in said output transformer secondary winding signaling current because of the unequal portions of the active tube plate circuit current flowing in the two portions of said primary winding, a transmitting circuit, and coupling means including a filter effective to pass only a preselected one of said side bands to couple said transmitting circuit to said secondary winding.
